[57] **CLAIM**

The ornamental design for a motorcycle stand or similar article, substantially as shown and described.

DESCRIPTION

FIG. 1 is a rear perspective view of a motorcycle stand or similar article showing my new design.

FIG. 2 is a top plan view thereof, drawn to an enlarged scale.

FIG. 3 is a front elevational view of FIG. 2.

FIG. 4 is a left end elevational view of FIG. 2.

FIG. 5 is a bottom plan view of FIG. 2.

FIG. 6 is a rear elevational view of FIG. 2.

FIG. 7 is a right end elevational view of FIG. 2.
